SHIPPING TAG DISPENSER

Herbert A. Salzbrenner, Denver, Colo.

Application May 23, 1938, Serial No. 209,550

10 Claims. (Cl. 312—56)

This invention relates to a dispenser, more particularly to a dispenser for dispensing shipping tags, checking tags, etc., one at a time. Its use is not limited to any particular type of tag since it can also be used for delivering cards, labels, or other relatively stiff sheets of material.

The principal object of this invention is to provide a neat, compact and efficient device of this character which can be operated with the fingers of one hand to deliver a tag between the thumb and finger of that hand so that the dispenser can be operated and the desired tag grasped with a single movement of one hand.

Another object of the invention is to provide a device of this character which will dispense a single tag from a pile of tags at each operation, and which can be readily adapted for tags or cards of various sizes and shapes.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view of one form of the improved dispenser.

Fig. 2 is a longitudinal section therethrough taken on the line 2—2, Fig. 1.

Fig. 3 is a cross section taken on the line 3—3, Fig. 2.

Fig. 4 is a cross section taken on the line 4—4, Fig. 2.

Fig. 5 is a longitudinal section taken on the center line of the dispenser.

Fig. 6 is a similar section illustrating the dispenser adapted for delivering small, card-like pieces.

Fig. 7 is a cross section taken on the line 7—7, Fig. 6.

The invention comprises an elongated inner casing 10 of a width to receive a pile of vertically aligned tags 11. This form of the invention is arranged for dispensing shipping tags or checking tags, such as used for baggage checking in railway stations and the like, of the type having an eyelet reinforcing ring 12 attached thereto.

The pile of tags is constantly urged forwardly in the casing 10 by means of a compression spring 13 which acts between the rear end of the

casing and a press plate 14. A lifting plate 15 extends across the inner face of the front end of the casing 10 and projects through guide slots 16 in the sides thereof. One edge of this plate is turned to form a narrow projecting flange 17 which, when the device is used for dispensing tags, contacts the eyelet ring 12 of the end-most tag to raise it upwardly from the pile.

The lifting plate 15 is actuated by means of a U-shaped lever 18 which extends along each side 10 of the casing 10 and entirely across the rear extremity thereof as shown in Figs. 5 and 6. The lever 18 is pivoted on suitable pivot members 19 at each side of the casing. The forward extremities of the lever 18 are narrowed, as shown at 15 20, to fit into end notches 21 in the lifting plate 15.

The forward extremities of the lever 18 are constantly forced downwardly by means of suitable leaf springs 22, there being one spring at 20 each side of the casing. These forward extremities can be lifted upwardly by the actuation of a press bar 23 extending across the top of the dispenser. The press bar 23 is supported upon push rods 24 each of which extends downwardly 25 to an actuating lever 25 pivoted at 26 to the sides of the casing 10. The position of the push rods is maintained by means of suitable guide members 38.

The forward extremities of the levers 25 are 30 positioned under the forward extremities of the lever 18 and are maintained in this position by means of suitable guide clips 27 attached to the levers 25 by means of suitable rivets 39 and extending upwardly alongside of the lever 18. 35

It can be readily seen that if the press bar 23 is forced downwardly it will force the rear extremities of the actuating levers 25 downwardly. This causes the forward extremities of the levers to rise against the lever 18 causing the latter to 40 raise the lifting plate 15. This causes the flange 17 of the plate 15 to engage the eyelet 12 of the end-most tag so as to elevate this tag above the others to the position shown in broken line in Fig. 5. The pivot points 26 of the lever 25 are 45 positioned toward the rear thereof so that a very slight movement of the press bar lifts the tag.

As each tag is dispensed, the spring 13 moves the press plate 14 forwardly until the entire 50 stack of tags is exhausted. The complete device and its operating mechanism may be covered and concealed by means of an ornamental housing 29 provided with a slot 30 for the exit of the tags. The housing 29 is preferably formed with a slid- 55

ing panel 31 to allow access to the casing 10.

For dispensing cards and smaller tags, an adjustable tag compartment is provided. This compartment consists of a base plate 32 which rests 5 in the bottom of the casing 10. Two adjustable side plates 33 are mounted on the base plate 32 by means of suitable clamp bolts 34, which pass through slotted holes, to allow the side plates to be adjusted toward and away from each other 10 to accommodate cards of any desired width. Each side plate supports an angular bottom plate 35 which forms a supporting bottom for the cards. These bottom plates are vertically adjustable on the side plates by means of bolts 36 15 and slotted openings 37 so that they may be raised or lowered to accommodate cards of various lengths or heights.

The same spring 13 and press plate 14 are employed with the adjustable compartment as 20 previously described. For use on cards, however, the lifting plate 15 is inverted so that the flange 17 extends along the bottom, as shown in Fig. 6. This plate is provided with two of the notches 21 in each of its ends to allow reversal and vertical adjustment thereof on the lever 18. Actuation 25 of the press bar 23 now causes the flange 17 to contact the bottom edge of the end-most card, lifting it from the pile and projecting it through the slots 28 and 30.

30 Thus, it can be readily seen that the same mechanism can be used with very little adjustment for handling cards or tags of any size, thus making it universally adaptable to the needs of the user.

35 The press bar 23 is so positioned that, as it is forced downwardly with the fingers the card or tag will be forced upwardly between the finger and thumb of that hand so that the entire operation is a single, simple movement of one hand.

40 While a specific form of the improvement has been described and illustrated herein, it is desired to be understood that the same may be varied, within the scope of the appended claims, without departing from the spirit of the invention.

45 Having thus described the invention, what is claimed and desired secured by Letters Patent is:

1. A card dispenser comprising: a casing for receiving a pile of cards; a compression spring 50 in said casing; a press plate actuated by said spring to force said pile toward one extremity of said casing; a lifting plate extending across the extremity of said casing against which the end-most card is pressed by said spring; means on said lifting plate for engaging said end-most card; actuating levers operatively connected at their one extremities to each extremity of said lifting plate; means for pivoting said levers intermediate their extremities, and a manually 55 actuated press bar connected with the other extremities of said levers to move said lifting plate upwardly across said pile to lift the end-most card therefrom as said press bar is pressed downwardly.

60 2. A card dispenser comprising: a rectangular casing for receiving a pile of cards; a compression spring in said casing mounted on the rear end thereof; a press plate actuated by said spring to force said pile toward the forward extremity 65 of said casing; a lifting plate extending across the forward extremity of said casing against which the end-most card is pressed by said spring; means on said lifting plate for engaging said end-most card; a U-shaped, pivoted, lever 70 extending around the two sides and across the rear of said casing; means on said lifting plate for engaging the forward extremities of said U-shaped lever; means for manually 75

5 rear of said casing; means on said lifting plate for engaging the forward extremities of said U-shaped lever; and means for manually actuating said U-shaped lever to cause said lifting plate to push the end-most card from said pile.

3. A card dispenser comprising: a rectangular casing for receiving a pile of cards; a compression spring in said casing mounted on the rear end thereof; a press plate actuated by said spring to force said pile toward the forward extremity 10 of said casing; a lifting plate extending across the forward extremity of said casing against which the end-most card is pressed by said spring; means on said lifting plate for engaging said end-most card; a U-shaped, pivoted lever extending around the two sides and across the rear of said casing; means on said lifting plate for engaging the forward extremities of said U-shaped lever; an actuating lever pivoted to each side of said casing adjacent to each extremity 20 of said U-shaped lever; a press bar extending across said dispenser; and push rods extending from said press bar to one extremity of each actuating lever so that pressure on said bar will cause said actuating levers to swing said U-shaped lever to cause the lifting plate to push the end-most card from said pile.

4. A card dispenser comprising: a rectangular casing for receiving a pile of cards; a compression spring in said casing mounted on the rear 30 end thereof; a press plate actuated by said spring to force said pile toward the forward extremity of said casing; a lifting plate extending across the forward extremity of said casing against which the end-most card is pressed by said 35 spring; means on said lifting plate for engaging said end-most card; a lever mechanism for moving the lifting plate laterally of said pile to force the end-most card therefrom; and an outer housing surrounding and enclosing said casing, said 40 housing being provided with a slot for the passage of said cards.

5. A tag dispenser comprising: a tag casing for receiving a horizontal series of vertically positioned tags of the type having eyelet reinforcing rings; spring means for forcing said pile forwardly in said casing; side walls of said casing provided near their forward ends with vertical guide slots; a lifting plate extending across the inner face of the forward extremity of said 50 casing and projecting through the said vertical guide slots in the sides thereof, the said spring means being adapted to press the forward tag of said pile against said plate, the latter being positioned below the reinforcing ring of said tag 55 so that when the plate is lifted, it will contact the eyelet reinforcing ring of that tag; manual means connected with said plate for forcing the latter laterally of said pile; and spring means connected to said plate for returning the latter 60 to its original position.

6. A card dispenser comprising: a rectangular-shaped casing for receiving a pile of cards; a compression spring in said casing mounted on the rear end thereof; a press plate actuated by 65 said spring to force said pile toward the forward extremity of said casing; a lifting plate extending across the forward extremity of said casing against which the end-most card is pressed by said spring; means on said lifting plate for engaging the forward extremities of said U-shaped lever; means for manually 70

actuating said U-shaped lever to cause said lifting plate to push the end-most card from said pile; and means for varying the width and depth of said casing to fit different sized cards.

7. A card dispenser comprising: a rectangular-shaped casing for receiving a pile of cards; a compression spring in said casing mounted on the rear end thereof; a press plate actuated by said spring to force said pile toward the forward extremity of said casing; a lifting plate extending across the forward extremity of said casing against which the end-most card is pressed by said spring; means on said lifting plate for engaging said end-most card; a U-shaped, pivoted, lever extending around the two sides and across the rear of said casing; means on said lifting plate for engaging the forward extremities of said U-shaped lever; means for manually actuating said U-shaped lever to cause said lifting plate to push the end-most card from said pile; and spring means for returning said plate.

8. A card dispenser comprising: a rectangular-shaped casing for receiving a pile of cards; a compression spring in said casing mounted on the rear end thereof; a press plate actuated by said spring to force said pile toward the forward extremity of said casing; a lifting plate extending across the forward extremity of said casing against which the end-most card is pressed by said spring; means on said lifting plate for engaging said end-most card; a U-shaped, pivoted, lever extending around the two sides and across the rear of said casing; means on said lifting plate for engaging the forward extremities of said U-shaped lever; an actuating lever pivoted to each side of said casing adjacent to each extremity of said U-shaped lever; a press bar extending across said dispenser; push rods extending from said press bar to one extremity of each actuating lever so that pressure on said bar will cause said actuating levers to swing said U-shaped lever to cause the lifting plate to lift the end-most card from said pile; and means for maintaining the position of said push rods and for guiding the same.

9. A card dispenser comprising: a rectangular-shaped casing for receiving a pile of cards; a compression spring in said casing mounted on the rear end thereof; a press plate actuated by

said spring to force said pile toward the forward extremity of said casing, a lifting plate extending across the forward extremity of said casing against which the end-most card is pressed by said spring; means on said lifting plate for engaging said end-most card; a U-shaped, pivoted, lever extending around the two sides and across the rear of said casing; means on said lifting plate for engaging the forward extremities of said U-shaped lever, an actuating lever pivoted to each side of said casing adjacent to each extremity of said U-shaped lever; a press bar extending across said dispenser; push rods extending from said press bar to one extremity of each actuating lever so that pressure on said bar will cause said actuating levers to swing said U-shaped lever to cause the lifting plate to lift the end-most card from said pile; and means for maintaining the position of said push rods and for guiding the same; and means for securing the said extremities of said U-shaped member to said actuating lever.

10. A card dispenser comprising: a rectangular-shaped casing for receiving a pile of cards; a compression spring in said casing mounted on the rear end thereof; a press plate actuated by said spring to force said pile toward the forward extremity of said casing, a lifting plate extending across the forward extremity of said casing against which the end-most card is pressed by said spring; means on said lifting plate for engaging said end-most card; a U-shaped, pivoted, lever extending around the two sides and across the rear of said casing; means on said lifting plate for engaging the forward extremities of said U-shaped lever; an actuating lever pivoted to each side of said casing adjacent to each extremity of said U-shaped lever; a press bar extending across said dispenser; push rods extending from said press bar to one extremity of each actuating lever so that pressure on said bar will cause said actuating levers to swing said U-shaped lever to cause the lifting plate to lift the end-most card from said pile; and means for maintaining the position of said push rods and for guiding the same; and means for securing the said extremities of said U-shaped member to said actuating lever.

HERBERT A. SALZBRENNER.
